US00D972671S

(12) **United States Design Patent** (10) **Patent No.:** **US D972,671 S**
(45) **Date of Patent:** **** Dec. 13, 2022**

(54) **OUTER COVER FOR VIBRATING FITNESS ROLLER**

(71) Applicant: **Hyper Ice, Inc.**, Irvine, CA (US)

(72) Inventors: **Anthony Katz**, Laguna Niguel, CA (US); **Bostjan Buc**, Mislinja (SI); **Jure Miklavec**, Skofja Loka (SI); **Andrej Senk**, Preddvor (SI)

(73) Assignee: **Hyper Ice, Inc.**, Irvine, CA (US)

(**) Term: **15 Years**

(21) Appl. No.: **29/771,688**

(22) Filed: **Feb. 24, 2021**

(51) **LOC (13) Cl.** **21-02**

(52) **U.S. Cl.**

USPC **D21/694**

(58) **Field of Classification Search**

USPC D24/211, 212, 213, 214, 215, 188, 141, D24/190, 200, 231, 106, 171; D30/160; D1/125-127; D21/680, 798, 792, 662, D21/804, 686, 671, 691, 682, 694, 687, D21/654, 487, 679, 684, 688, 412, 685, D21/400, 791, 725, 386; D7/624.2; D8/303

(57) **CLAIM**

The ornamental design for an outer cover for vibrating fitness roller, as shown and described.

DESCRIPTION

FIG. 1 is a front perspective view of an outer cover for vibrating fitness roller of the present design;

FIG. 2 is a rear perspective view thereof;

FIG. 3 is a top view thereof, the bottom view being a mirror image thereof;

FIG. 4 is a left side view thereof, the bottom view being a mirror image thereof;

FIG. 5 is a front view thereof; and,

FIG. 6 is a rear view thereof.

The broken lines in the drawings are for the purposes of illustrating portions of the outer cover for vibrating fitness roller, which form no part of the claimed design.

1 Claim, 5 Drawing Sheets
